ELECTRIC-SWITCH MECHANISM.

1,228,905.

Specification of Letters Patent.

Patented June 5, 1917.

Application filed November 6, 1915. Serial No. 60,046.

To all whom it may concern:

Be it known that I, DAVID D. GORDON, a citizen of the United States, and a resident of Chicago, in the county of Cook and State of Illinois, have invented a certain new and useful Electric-Switch Mechanism; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

15 This invention relates to electric switching devices of the quick make and break type, and particularly to switches of this character of the pull-chain type and intended for use in electric lamp sockets or the 20 like.

The object of my invention is the provision of an improved switch of the character described which is simple, durable and inexpensive in its construction, quick and 25 accurate in its action, and has the bridging member thereof locked against circuit making and breaking movements until the tension actuated tripping means has been moved a predetermined extent and had a 30 predetermined amount of energy stored therein for shifting the bridging member. Further objects and advantages of the invention will be apparent from the following detailed description thereof.

35 While the invention in its broader aspect is capable of embodiment in numerous forms, a preferred form and one modified form thereof are illustrated in the accompanying drawings, in which,—

40 Figure 1 is a central longitudinal section of a socket embodying the preferred form of my switch with the switch in full. Fig. 2 is an inner end view of the socket and switch with the cap portion of the socket 45 removed. Figs. 3, 4 and 5 are sectional details of the switch mechanism illustrating different operating positions of the parts. Fig. 6 is a perspective view of the switch mechanism with the actuating means for the 50 shifting movements of the bridging mechanism removed. Fig. 7 is a different central longitudinal section of the socket from that shown in Fig. 1 with the switch mechanism in full. Fig. 8 is a view of the coupling end 55 of the socket. Figs. 9 and 10 are perspec-

tive views of the bridging member and central slide, respectively, and Fig. 11 is an enlarged perspective view of a slightly modified form of the switch mechanism.

Referring to the drawings, 1 and 2 designate the base and cap parts, respectively, of the interior insulating body of a socket, and 3 and 4 designate the body and cap portions, respectively, of an inclosing shell for the insulating parts of the socket, as is customarily employed in certain types of sockets of the character described. The parts 3 and 4 of the shells are preferably secured together in any suitable or convenient manner as is well understood in the art.

The parts 1 and 2 of the interior insulating body of the socket coöperate, in the present instance, to form a closed or insulatingly closed, chamber 5 in which the switch mechanism is located. The insulating cap 2 and the shell cap 4 have centrally disposed registering openings 6 through which its terminal wires 7 may be introduced into the chamber 5. The cap 2, in the present instance, is provided at its inner side or interiorly of the chamber 5 with a pair of binding screws 8, 8 which serve to bind the terminal wires 7 to respective contact plates 9 and 10, which are carried by the insulating cap on the inner side thereof. These contact plates, in the present instance, have fingers 11 and 12, respectively, projecting therefrom into the chamber 5 lengthwise of the socket and these fingers, when the insulating parts 1 and 2 are in assembled position, have 90 contact with respective contact fingers 13 and 14, which rise within the chamber 5 in substantial parallelism with the fingers 11 and 12.

The contact 14, in the present instance, projects from or has electrical connection with the inner end of the customary screw shell 15 which is secured to the outer end of the insulating part 1 and forms the side contact for the lamp, connecting plug, or other attachment inserted into the socket, as is well understood in the art. The screw shell 15 is insulatingly spaced from the outer end of the shell part 3 by an insulating sleeve 16. The other contact 13 of the set, which is carried by the insulating part 1, is intended to have connection with the usual center contact 17 of the socket through the bridging member of the switch mechanism, which forms the present invention.

The bridging member of the switch is designated 18 and is carried for rocking movements within the chamber 5 by the spaced upstanding arms 19 of a chair or bracket member 20 that is mounted on the bottom of the chamber 5. The bridging member 18, in the present instance, comprises two side bars 21, 21 of pressed fiber or other suitable insulating material of a rigid nature, and these bars are connected together at one end by a cross-piece 22, preferably, but not necessarily, of metal, which carries the bars 21, 21 at their inner ends and rigidly space them apart, as best shown in Fig. 6. The cross-piece 22 is provided at its ends with axially aligned trunnions 23, which are journaled in bearing openings in the respective upstanding arms 19 of the bracket 20, thus permitting the bridging member to have rocking movements relative to said bracket. Each bar 21 of the bridging member is provided at its outer end at the outer side thereof, in the present instance, with a contact part 24 and these contact parts are electrically connected by a bridging piece 25, which extends over the top of the bridging member.

The bars 21 are connected adjacent to the inner or pivoted end thereof with a cross-piece 26, which is provided with an opening 27 therethrough through which a slide member 28 has reciprocatory movements and which co-operates with the cross-piece 26 to control the shifting movements of the bridging member 18. The slide 28 has one end 30 projecting through an opening or cut-away portion 29 in the cross-piece 22 of the bridging member and rests on the top of an upstanding arm 30 of the bracket 20. This end of the slide 28 is also adapted for attaching 40 to a pull chain or tension means 31. The opposite end portion of the slide 28 is guided for reciprocatory movements by a pair of upstanding arms 32 on the adjacent end of the bracket 20, said arms being notched at 45 their inner sides, as at 33, to slidably receive the respective edges of the slide 28. The opening 27 of the bridging member cross-piece 26 is of greater width than the thickness of the slide 28 to permit the bridging member to have limited rocking movements relative to said slide, such movements being limited by the upper and lower edge walls of the opening co-acting with the slide. The slide 28 normally stands in the 55 forward position shown in Figs. 1, 3 and 6 due to the action of a spring finger 34 thereon, which finger is carried by the bracket 20. The forward movements of the slide under the influence of the spring 34, are limited by 60 contact of the free end of the slide or of a part carried thereby with the adjacent wall of the chamber 5, as shown in Figs. 1 and 2. When the slide 28 is in its forward or normal position the bridging member 18 is 65 locked against shifting movements by a lug

35 projecting inward from one or both ends of the opening 27 in engagement with the upper or lower adjacent edge of the slide 28, as the lugs may be disposed below or above the slide, depending on the position of the 70 bridging member. The slide 28 is provided in each side edge thereof with a notch 36, which, when the slide 28 has been retracted a predetermined extent from its normal forward position move into register with the 75 respective lugs 35 and permit a passage of such lugs through said notches and a consequent shifting of the position of the bridging member, such shifting movements being guided as hereinafter described. Upon a release of the tension applied to the slide 28 through the chain 31, or in any other suitable manner, after a shifting of the bridging member, the slide 28 returns to its normal forward position, moving the notches 80 36 out of register with the lugs 35 and locking said member in its shifted position, which position is maintained until the slide has been again retracted to bring the notches 36 thereof into register with the lugs 35. 85 When the notches 36 of the slide 25 have been moved into register with the lugs 35 the retracting movement of the slide 28 is stopped, in the present instance, by one or more shoulders 37 on the rear end portion of 90 the slide 28 moving into contact with a registering portion of the cross-piece 22 at the pivoted end of the bridging member 18.

The slide 28 is provided in its forward end portion with an elongated opening 38, 100 which, when the slide is in its forward or normal position, extends to near the control strip 26 of the member 18. The outer end wall of the slide opening 38 is also provided with an opening 39. A plunger 40 is 105 projected through the opening 39 and into the opening 38 lengthwise of the latter and has its inner end terminating in a fork-like part 41, the arms of which extend in opposite directions in the plane of shifting 110 movements of the bridging member 18. The plunger 40 has its inward or rearward movements relative to the slide stopped by the contact of a flattened head 42 with the outer end of the slide and the plunger is 115 of suitable length to adapt it, when at the limit of its inward movement, to extend to near the inner end of the slide opening 38, as best shown in Figs. 2 and 3. A coiled compression spring 43 is carried by the 120 plunger 40 within the opening 38 and has its other end thrust against the outer end wall of said opening, thereby normally acting to retain the plunger at the limit of its inward movement relative to the slide.

It is evident by reference to Figs. 3, 4 and 5 that upon an inward movement of the slide 28 from the normal position shown in Fig. 3, one of the arms 41 at the forked end of the plunger will contact with the reg- 125 130

istering edge wall or portion of the control strip 26, which, in Fig. 3, is in contact with the under side of the slide, thus holding the plunger against inward or rearward movements with the slide and causing a compression of the spring 43, whereby to store considerable energy therein for effecting a shifting of the bridging member when the slide 28 has been moved a sufficient distance 5 to place the notches 36 in register with the lugs 35 on the bridging member. Fig. 4 indicates the position of the switch parts immediately prior to the notches 36 moving into full or releasing register with the lugs 15 35, and shows that the plunger 40 under the action of the spring 43 is exerting a downward shifting movement on the coacting part 26 of the bridging member, such thrust being exerted in a line which is tangential 20 to a circle struck about the turning axis 23 of the bridging member instead of being directed toward such axis. Fig. 5 illustrates the position of the switch parts immediately after the position of the bridging member 25 has been shifted from the position shown in Fig. 4, and before the retracting or rearward pulling tension on the slide 28 has been released. Upon a releasing of the slide 28 and its return to normal position 30 with respect to the frame 20, as shown in Fig. 3 and in position for the upwardly projecting arm 41 at the inner end thereof to stand in register with the upper edge portion of the control strip 26, whereby the next 35 rearward movement of the slide will cause the plunger to exert its pressure on said upper edge portion of the strip 26 and effect an upward shifting of the bridging member 18 when it has been released for 40 such purpose by reason of the notches 36 and lugs 35 moving into register. The coacting of the flat faced head 42 of the plunger 40 with the registering end of the slide 28 causes a drawing up or central registering 45 of the plunger with the slide as is evidenced by Fig. 3.

It will be understood that when the bridging member 18 is in one position of its movements the contact 24 at the forward or free 50 end of one bar 21 makes contact with a registering portion 13^a of the contact finger 13, and the contact 24 at the free end of the other bar 21 makes contact with a registering part 19^a, which either forms a part of 55 or is electrically connected to the center contact 17, as shown in Fig. 1. When the bridging member is in contact with the contacts 13^a and 17^a, a circuit is completed between said contacts through the bridging 60 piece 25 of the bridging member. The provision in the bridging member 18 of the bars 21 of insulating material effectively insulates the contacts 24, 24 and bridging piece 25 from the other metallic parts of 65 the switch mechanism, and such construction

is preferable to making all the switch parts of conductive material, whereby such parts are all charged when the bridging member is in circuit closing position, and which necessitates an insulating of the pull-chain 31 70 or other control means from the switch mechanism.

In the modification illustrated in Fig. 9, 50 designates the bridging member which is the same in construction as the bridging 75 member of the preferred form, 51 the chair or bracket to which the bridging member is pivoted, and 52 the slide which projects through an opening 53 in a cross-piece 54 of the bridging member and is provided 80 with a single notch 55 in one side edge thereof for coacting with a lug 56 at the respective end of the opening in the strip 54 to control the shifting movements of the bridging member, the same as such shifting 85 movements are controlled in the form hereinbefore described. The slide 52 has its forward end portion slidingly projected through a guide opening in an upstanding arm 57 at the forward end of the bracket 90 51 and is provided without said guide arm with a laterally bent or extended portion 58, which is intended to coact with the outer side of said arm to limit the rearward or retracting movements of the slide. The 95 part 58 of the slide extends beyond one side edge of the slide 52 and is provided with a bearing head 59 through which a plunger 60 slidingly projects, said plunger being the same in construction and action as the plunger 40 of the preferred form. This plunger extends rearward from the head 59 at one side of the guide arm 57 in position for its inner end to coact with a registering portion of the cross strip 54 of the bridging 100 member. 61 designates the coiled compression spring which encircles the plunger 60 and co-operates with the plunger to actuate the shifting movements of the bridging member, and 62 designates the spring finger, 110 which normally maintains the slide in its forward bridging member locking position. The operation of my improved switch is as follows: Supposing the bridging member 18 to be in the open position shown in 115 Figs. 1 and 3, the operator pulls on the chain or tension device 31, thereby effecting an inward or rearward movement of the slide 28 to the full retracted position shown in Fig. 5. Upon such movement of the slide 120 the forked inner end of the plunger 40 engages the registering lower edge portion of the control strip 26 of the bridging member and stands stationary in such engaged position while the slide completes its rearward 125 movement and effects a storing of energy in the plunger spring 43 by compressing the same. When the slide has reached the limit of its rearward movement, the notches 130 therein will have moved into register with

the respective lugs 35 of the control strip 26, thereby unlocking or releasing the bridging member to permit it to be quickly shifted, by the spring action of the plunger 40 thereon, to the circuit closing position shown in Fig. 5. The operator then releases the slide 28 to permit it to return to its normal position, which return effects a release of the forked end engagement of the 10 plunger with the cross-piece 26 of the bridging member and permits said plunger to return to its normal aligned position with the slide, in which position the forked end of the plunger stands in register with the 15 upper edge portion of the cross-piece 26, whereby the next rearward movement of the slide will cause the plunger to engage said upper edge portion of the cross-piece 26 and effect an inward or circuit breaking shifting of the bridging member when the slide has been moved a sufficient extent to place the notches 36 thereof in register with the 20 lugs 35. Inasmuch as the preferred and modified forms of the invention are very 25 similar the operation of the latter will be understood from the foregoing.

While I have herein shown and described two specific embodiments of my invention for illustrative purposes, it is to be understood that the invention is not limited to the mere detail or relative arrangement or construction of the parts, but that deviations from the illustrated forms of the invention may be made without departing 35 from the spirit of the claims.

Having thus described my invention, what I claim as new, and desire to secure by Letters Patent, is,

1. In an electric switch, spaced contacts, 40 and a bridging element mounted for oscillatory movements into and out of bridging connection with said contacts, said element having spaced side bars of insulating material rigidly connected at the inner or pivot- 45 ed end of the element, and electrical conductive means carried by and connecting the outer ends of said bars for engaging and bridging said contacts when said element is in circuit bridging position.
2. In an electric switch, a bridging element having spaced electrically connected side arms forming contact parts, said element being mounted for rocking movements in a plane at right angles to the plane in which 55 said side arms are spaced and having a cross-bar connecting said arms, said bar having an opening therethrough lengthwise of said element, a control member reciprocally movable lengthwise of said element and 60 projected through said bar opening, said member and bar having parts which cooperate to lock the element against rocking movements until the member has been moved a predetermined extent, and means carried 65 by said member and operable to impart quick

shifting movements to said element when released for movement by the control member.

3. In an electric switch, a bridging element mounted for rocking movements and having electrically connected side arms 70 forming contact parts and spaced transversely of the plane of rocking of the element, a bar connecting said side arms and forming a part of said element, said bar being spaced from the rocking axis of said 75 element, a control member projected through said bar for reciprocatory movements lengthwise of the element and normally standing in one position of its movement relative thereto, said member and bar coöperating to lock the element against rocking movements except when the member has been moved a predetermined extent from normal position, and spring means carried by said bar and operable to impart quick 80 rocking movements to said element in first one direction and then the other when the member is successively moved to release the element.

4. In an electric switch, a bridging element mounted for rocking movements and having electrically connected side arms forming contact parts and spaced transversely of the plane of rocking of the element, a control member mounted between 95 the side arms of said element for reciprocatory movements lengthwise thereof and relative thereto and normally standing in one position of its movement, said member and element having parts which coöperate to 100 lock the element against rocking movements except when the member has been moved a predetermined extent, and means actuated by movements of said member from normal position to store energy therein and to act 105 on said element to move it first in one direction and then the other when successively released by said member.

5. In an electric switch, a bridging element mounted for rocking movements to 110 make and break an electric circuit, a control member guided for reciprocatory movements lengthwise of said element and normally standing in one position of its movement, said member and element having parts which 115 coöperate to prevent shifting movements of the element except when the member has been moved a predetermined extent from normal position, a plunger carried by said member for lengthwise and transverse movements relative thereto, a coiled compression spring encircling said plunger and interposed between respective parts of said member and plunger to yieldingly retain the plunger in one position relative to the control member, said plunger being operable by movements of said member from normal position and by said spring to exert quick shifting movements to the element in first 125 one direction and then the other when re- 130

leased by successive movements of the member from normal position.

6. In an electric switch, spaced contacts, a bridging element mounted for rocking movements and movable to make and break connection between said contacts, said element having a part projecting therefrom in spaced relation to its rocking axis and transverse to its plane of rocking movements, a reciprocally movable control member movable transverse to the rocking axis of said element and normally standing in one position of its movement, said member and element part co-

operating to lock the element against rocking movements except when the member has been moved a predetermined extent from normal position, and means actuated by movements of said member from normal position to store energy therein and to act on said element to move it first in one direction and then the other when successively released by said member.

In testimony whereof, I have hereunto signed my name to this specification.

DAVID D. GORDON.
